Willy H. Wong(57) **CLAIM**

The ornamental design for a toy lawnmower, as shown and described.

DESCRIPTION

FIG. 1 is a right side view of a toy lawnmower in accordance with the present invention.

FIG. 2 is a left side view thereof.

FIG. 3 is a front view thereof.

FIG. 4 is a rear view thereof.

FIG. 5 is a top view thereof; and,

FIG. 6 is a bottom view thereof.

The broken lines show portions of the toy lawnmower that form no part of the claimed design.
